UNITED STATES PATENT OFFICE.

ROSWELL A. DANDARAW AND GEORGE E. GORDON, OF RENSSELAER,
NEW YORK.

DESIGN FOR A GAME-BOARD.

SPECIFICATION forming part of Design No. 27,591, dated August 31, 1897.

Application filed July 21, 1897. Serial No. 645,474. Term of patent 7 years.

To all whom it may concern:

Be it known that we, ROSWELL A. DANDARAW and GEORGE E. GORDON, of Rensselaer, in the county of Rensselaer and State of New York, have invented and produced a new and original Design for a Game-Board, of which the following is a specification, reference being had to the accompanying drawings, forming a part thereof, in which—
10 Figure 1 is a plan view of a game-board embodying the features of our design, and Fig. 2 is a transverse section on the line 2 2 of Fig. 1.

The design relates to that class of game-boards upon which movable objects are to be placed.

The leading features of the design consist

of a base A and a barrier B, resembling a bar, supported upon the base, and a series of shorter barriers C, likewise resembling bars 20 and apparently crossing the main barrier, the combined barriers forming a group of pockets D open upon one side.

A minor feature of the design consists in the raised margin E of the base. 25

We claim—

The design for the game-board herein shown and described.

ROSWELL A. DANDARAW.
GEORGE E. GORDON.
